UNITED STATES PATENT OFFICE.

JONAS NORTHRUP, OF HOPEDALE, MASSACHUSETTS, ASSIGNOR TO
DRAPER COMPANY, OF HOPEDALE, MASSACHUSETTS, A CORPO-
RATION OF MAINE.

FILLING-REPLENISHING LOOM.

No. 846,048.

Specification of Letters Patent.

Patented March 5, 1907.

Application filed June 4, 1906. Serial No. 320,019.

To all whom it may concern:

Be it known that I, JONAS NORTHRUP, a citizen of the United States, residing in Hopedale, county of Worcester, and State of Massachusetts, have invented an Improvement in Automatic Filling-Replenishing Looms, of which the following description, in connection with the accompanying drawings, is a specification, like letters on the drawings representing like parts.

This invention relates to that type of loom wherein the running filling is replenished automatically and wherein two filling-detectors are provided, arranged to detect presence or absence of filling on alternate picks.

Looms of this general type have been so arranged that the actuation of the replenishing mechanism has been effected directly by or through detection of filling failure by one detector and indirectly when such filling failure is detected by or through the other detector, and means have been provided to arrest take-up by such detecting action of either fork.

A loom of this general character forms the subject-matter of United States Patent No. 789,291, granted to me May 9, 1905, the replenishing mechanism therein shown being of the well-known "Northrop" type, wherein the running shuttle is provided automatically with a fresh supply of filling when required. Such filling replenishment may be called for prior to complete exhaustion of the filling in a "feeler-loom," or it may be called for upon failure of the filling—that is, when the filling by running out or by breakage fails or is absent when the detecting action of the detector occurs.

In my present invention I am dealing more particularly with non-feeler looms; wherein a change in the operation of the loom—such as filling replenishment or loom stoppage, or both—is effected automatically upon filling failure or absence.

In United States Patent No. 691,481, granted to me January 21, 1902, a loom is shown provided with means to effect filling replenishment on the pick on which filling failure or absence is detected, the detection of the presence or absence of the filling taking place on the pick of the shuttle to the replenishing side of the loom. Such an arrange-

ment provides for immediate replenishment of the running filling, if the latter fails on the pick toward the replenishing side, and hence no arrest of the take-up is required. If, however, the failure takes place on the opposite pick, detection of such failure is not made until the next or detecting pick, and hence there will be two picks in which the filling is improperly laid, and if take-up is not arrested for those picks a thin place will be made in the cloth.

My present invention has for its object the production of a loom so constructed and arranged that take-up is arrested when necessary to prevent the formation of thin places in the cloth, and filling replenishment is effected upon detection of filling failure, and in the practical embodiment of my invention herein illustrated and described such replenishment is effected on the pick on which failure is detected—viz., on the pick toward the replenishing side of the loom.

I have herein provided two filling-detectors to detect on alternate picks, one detector controlling the replenishing mechanism and the other detector controlling the take-up mechanism, and I have so arranged the apparatus that when take-up is arrested by or through detecting action of its controlling detector take-up will not be resumed until such detector indicates the proper laying of the filling.

The mechanism for carrying out my invention is simple and direct in action, and certain valuable features inherent in the structures embodied in my patents hereinbefore referred to are also comprehended herein in a novel and efficient manner.

The various novel features of my invention will be fully described in the subjoined specification, and particularly pointed out in the following claims.

I have illustrated my invention in connection with filling-replenishing mechanism of the Northrop type; the same as shown in the patents referred to, though my invention is not restricted thereto, as will appear more clearly hereinafter.

Figure 1 is a top plan view, centrally broken out, of a sufficient portion of a loom and automatic filling-replenishing mechanism to be understood, with one embodiment

of my invention applied thereto. Fig. 2 is a transverse sectional view thereof on the line 2-2, Fig. 1, looking toward the right, the parts being in the same relative position. Fig. 3 is a transverse section on the line 3-3, Fig. 1, but looking toward the left, showing some of the means for effecting actuation of the replenishing mechanism. Fig. 4 is a front elevation of a portion of the lay adjacent the mouth of the replenishing shuttle-box with the actuator for the replenishing mechanism. Fig. 5 is a front elevation of the take-up mechanism shown in plan, Fig. 1. Fig. 6 is an enlarged detail in plan of the filling-detector, which controls the take-up, and some of the parts coöperating therewith in normal position. Fig. 7 is a like view showing the change in relative position of the parts brought about by detection of filling failure by said detector. Fig. 8 is a plan view of the outer end of the slide, on which is mounted the detector or fork shown in Figs. 7 and 8. Fig. 9 is a perspective view of the device by or through which arrest of take-up is maintained until the filling is laid properly in front of the take-up-controlling detector. Fig. 10 is an enlarged top plan view of the other filling-detector, the means by or through which detecting action of such detector causes the actuation of the replenishing mechanism, and the means to govern said detector on the non-detecting picks, all in the position assumed when the detector is ready to detect. Fig. 11 is an inner side elevation of such parts, the nearer side of the detector-support being broken out to show parts beyond it. Fig. 12 is a view similar to Fig. 11, but showing the detector tilted or moved out of the shuttle-path, so that the shuttle when picked from the replenishing shuttle-box will clear the detector, a portion of the lay and parts mounted thereon being shown in dotted lines. Fig. 13 is a view similar to Fig. 11, but showing the detector as returning to detecting position.

While herein, as in my Patent No. 691,481, filling replenishment takes place on the pick, in which its failure is detected on the shot of the shuttle toward the replenishing side of the loom, the means for governing the detector on the intervening picks is very different.

In the patent the detector is mounted on a support which is moved rearward on the detecting-pick and moved forward on the next or return pick, while herein the detector-support is fixed or stationary, and the detector is positively tilted on the non-detecting picks, as will be clearly described hereinafter.

Referring to Fig. 1, the lay A^3 , shuttle-boxes B^X thereon, the shuttle S^X of an automatically self-threading type, the filling-replenishing mechanism at the loom side adjacent the shuttle-box B^X and including the filling-feeder F , (only a portion of the latter

being shown,) and the transfferer F' to transfer the filling carriers or bobbins b , Fig. 3, from the feeder to the shuttle, to thereby replenish the supply of running filling, the stud F^X , on which the transfferer rocks, and the retracting-spring F^2 for such transfferer, may be and are all substantially as common in the Northrop type of loom—such, for instance, as shown in United States Patent No. 529,940, dated November 27, 1894.

Herein the transfferer is provided with a short depending extension 1, which carries a notched dog 2, Fig. 3, to be at times engaged by an actuator shown as a bunter 3, fast on a short rock-shaft 4, mounted in a sleeve-like bearing 5 on the lay, said rock-shaft having at its inner end an upturned short arm or trip 6 rigidly secured to it and adapted to be moved rearwardly into the clearance 7, Fig. 1, at the inner end or mouth of the replenishing-box B^X .

A spring 9, connected at its ends to the rock-shaft and to the bearing 5, respectively, is so wound as to normally maintain a shoulder 10 of the actuator or bunter 3 on a stop 11, herein shown as forming a part of the bearing-casting 5. The actuator or bunter when in such position is so held as to travel below and clear of the dog 2 in the normal operation of the loom.

When the short arm or trip 6 is swung rearwardly against the action of spring 9, the actuator or bunter 3 will be thereby lifted into position to engage the dog 2 as the lay beats up, and as the beat-up is completed the transfferer F' will be depressed, to thereby insert a fresh filling-carrier into the shuttle then in the replenishing-box B^X , while the filling-carrier then in the shuttle will be ejected. As will appear hereinafter, this operative positioning of the actuator is effected by or through detection of filling failure by one of the two filling detectors or forks with which the loom is equipped and in such manner that the replenishing mechanism will be actuated on the pick on which such filling failure is detected and indicated.

The two filling-detectors are shown in plan view in Fig. 1, and it will be seen that they are located at opposite sides of the loom, and in the present embodiment of my invention the operation of the replenishing mechanism is controlled wholly by the right-hand detector—that is, the one at the same side of the loom—and this detector and the mechanism coöperating therewith will now be described.

A substantially L-shaped support 12 13 is rigidly secured, as by bolts 14, Fig. 2, to a bracket 15 on the front of the loom and back of the breast-beam A^4 , the part 13 of the support being extended rearwardly and in a substantially horizontal direction, and, as shown in Fig. 10, said part is bifurcated to form a fixed supporting means for the filling detector 130

or fork 16, fulcrumed at 17 to tilt or rock in a manner common to filling-forks.

One of the tines, as 16^x, of the fork is preferably covered with felt, flannel, or other friction-inducting material to enable the fork to have a better action when engaged by the filling. This fork is located opposite the grid or grating 18 on the lay adjacent the mouth of the replenishing shuttle-box B^x, and referring to Fig. 12 it will be seen that the upper end of the grid is bent rearwardly to a greater extent than is usual in fork-grids. This prevents any engagement of the fork with the grid when upon filling failure the fork is not tilted, for by reference to Fig. 12 it will be seen that when the lay is at front center the upright front portion of the grid or grating is well in front of the fulcrum 17 of the fork. Said fork is provided with a forward extension or tail 19, which at times serves to lock in operative position the controlling device to be described, and whereby when the device is so locked the actuation of the replenishing mechanism will be effected.

25 A transverse pin 20, between the bifurcated sides of the part 13 of the fork-support, has mounted upon it a sleeve-like hub 21, Fig. 10, of the controlling device, the latter being shown as a species of bell-crank comprising an upturned member 22 and a slightly depending and forwardly-extended member 23, the latter normally lying below the support, as shown in Figs. 11 and 12, while the upright arm or part 22 is located in front of the path of movement of the fork extension 19. The rear face of the said part 22 serves at times as a shoulder against which abuts the free end of the extension 19, as shown in Fig. 11, and at that time the fork is in untilted or detecting position, and when the controller is so locked it will be clear that it cannot be tilted or rocked on its fulcrum 20 in the direction of the arrow 24. Movement of the controller in the opposite direction is limited by a stop 25 formed on one of the sides of the part 13 of the fork-support.

50 The foot 23 is laterally offset to swing in a vertical path outside of the horizontal portion of the fork-support, as will be clear from an inspection of Fig. 10, and such foot is normally in the path of movement of and adapted to engage the short arm or trip 6 on each forward beat of the lay.

55 If the controller is locked in its normal position, as in Fig. 11, when the lay beats up, the trip as it comes forward engages the under edge of said foot 23, and as the foot cannot give the trip is pushed backward into the clearance 7 against the action of the spring 9, rocking the shaft 4, and thereby moving the actuator or bunter 3 into operative position to engage the dog 2 and effect filling replenishment as the forward beat of the lay is completed.

It will be noted in Figs. 11 and 12 that the under face 23^x of the foot is forwardly and downwardly inclined to assist in such swinging movement of the trip.

If the controlling device is unlocked—as, for instance, in Fig. 12—the trip 6 will wipe along the lower edge of the foot and will slightly rock the controlling device on its fulcrum 20, so that no change in the relative position of the actuator or bunter 3 will take place, and at such time no operation of the replenishing mechanism will be effected.

Whenever the detector or fork 16 is tilted, whether by engagement with filling or otherwise to withdraw the locking extension 19 from engagement with the controlling device, the latter is free to be rocked or turned in the direction of the arrow 24, Fig. 11.

The upper end of the part 22 of said controlling device is prolonged upwardly and forwardly to present an inclined face 26 for a purpose to be referred to.

A cross-bar 27 on the fork-support serves as a stop to limit downward movement of the locking extension 19, Figs. 10 and 11, and just in front of said stop or cross-bar is fulcrumed at 28 a depending finger 29, having an eccentric weighted head 30, the latter serving to normally maintain the finger in the position shown in Figs. 10, 11, and 12, the finger being so located that when the lay beats up and filling is present to tilt the fork the finger will prevent such filling from passing under the tines as the lay reaches front center.

The coöperation of the finger and fork is well shown in Fig. 12, the finger at such time passing between two of the fork-tines. The cross-bar 27 serves also to limit rearward swing of the finger, which may be said to act as a guard to prevent movement of the thread under the tines of the fork.

The fork 16 detects presence or absence of filling on every alternate pick, such picks being those on which the shuttle is moving toward the replenishing side of the loom, and detection takes place on the forward beat of the lay after the shuttle has passed beyond the range of such fork.

If for any reason the shuttle should not be properly boxed, but should project far enough from the mouth of the shuttle-box to strike the fork, the latter will be tilted, thereby preventing any operation of the replenishing mechanism, and as the fork is perfectly free to tilt no injury will result thereto. This tilting of the fork by the shuttle when improperly boxed enables the fork to also act as a shuttle-feeler, because even if the filling should have failed the replenishing mechanism cannot operate if the fork is tilted.

When the filling fails on the detecting-pick of the fork 16, the latter will not be tilted as the lay beats up, and the extension 19 there-

for locks the controlling device so that the foot 23 thereof will cause the operation of the replenishing mechanism, as has been explained.

Whether or not the fork has been tilted on the detecting-pick it is necessary to prevent the engagement of the fork and shuttle when the latter is on its return-pick; leaving the box B^X, and I have provided means to positively 10 tilt the fork on such return-pick, to thereby withdraw it from the shuttle-path, and such means are also made effective to prevent any detecting action whatever of the fork on the return-pick or otherwise the replenishing 15 mechanism would be operated on each of such return-picks, as will be manifest.

The fork-head is provided with an upright transverse projection 31, lying in the path of movement of the laterally-extended end 32 20 of a vibrating member 33, pivotally mounted at 34 on the upper end of a cam follower or vibrator 35, suitably fulcrumed at 36 on the loom-frame and actuated by a cam 37 on the cam-shaft 38. The vibrating member 33 is 25 provided with two depending guides 39 40, which straddle one of the sides of the part 13 of the fork-support, and the free rear end of said member 33 slides on the top of such side, so that as the vibrator 35 oscillates the member 33 will move forward and back along the substantially horizontal top of the support. At the outer end of its stroke the vibrating member 33 is in the position shown in Figs. 1, 2, 10, and 11, the lateral extension 32 being 30 then just in front of the projection 31 on the fork. The inner guide 40 is provided with a lateral lug 41, movable in a path above the stop 25, hereinbefore referred to. The cam 37 is so shaped and timed that the member 33 begins to move rearwardly just as the fork 35 is about to detect presence or absence of filling failure and reaches the position shown in Fig. 12 at the time the lay reaches front center. The lateral extension 32 is thereby 40 brought against the projection 31, and the fork is held in the tilted position shown in Fig. 12, and as the vibrating member 33 completes its rearward stroke the fork is tilted an additional amount until the extension 32 45 wipes over the projection 31, as in Fig. 13, practically releasing the fork. By this time, however, the lug 41 has moved into engagement with the controlling device and has tilted that into the position shown in Fig. 13, 50 moving the incline 26 to the rear, so that the fork extension 19 drops thereonto; but it can only drop to the position shown in Fig. 13, maintaining the fork in a tilted position, and at the same time the foot 23 is lifted into 55 an inoperative position.

When the vibrating member 33 tilts the fork, as described, the shuttle is free to be picked from the replenishing-box and will be shot across the lay without any possibility of 60 interference with the fork, and when the

parts assume the position shown in Fig. 13 it will be manifest that as the lay beats up the filling on such return pick no actuation of the replenishing mechanism can be effected by or through the fork, for the latter is somewhat 70 tilted, and, furthermore, the controlling device is in an inoperative condition. The shuttle is now picked from the non-replenishing box B, and the fork 16 must be in detecting position by the time the shuttle has 75 passed the grid or grating 18. To this end the vibrating member 33 is moved on its forward stroke, and during this stroke the movement of the lug 41 allows the controlling device to gradually resume its normal position, 80 the extension 19 sliding down the incline 26 toward locking position, and at the same time the lateral extension 32 on the member 33 wipes over the curved edge 42 of the projection 31 on the fork and acts to positively 85 return the fork to detecting position, the latter being shown in Fig. 11. This return is all effected before the lay reaches the detecting point on its forward beat.

The incline 26 by its co-operation with the 90 fork 19 also provides for a gradual return of the tilted fork to detecting position, and thereby obviates any improper jumping or vibrating of the fork, and this function is also enhanced by decreasing the distance which the 95 extension must drop from its highest point before being engaged by some stopping part.

On every detecting pick it will be observed that the fork which controls the operation of the replenishing mechanism is in detecting 100 position and the controlling device is locked in its operative position, and it will be also observed that on every return or non-detecting pick such fork is positively tilted, and through the means described there is no possibility of the replenishing mechanism being 105 operated on such pick. The positive tilting of the fork on such intervening picks is also timed to enable the fork to clear the outgoing shuttle from the replenishing-box B^X. A 110 suitable spring 43 acts upon the vibrating member 33 to depress the latter and prevent any improper jumping in its movements.

As filling is replenished on the pick on which failure is detected by the fork 16 take-up is not arrested, nor should it be; but I have provided means for arresting take-up if the filling fails on the return picks—that is, the picks of the shuttle away from the replenishing side of the loom—and for this purpose I have provided the second filling detector or fork, the function thereof being to control the take-up mechanism and to arrest and maintain arrested the taking up of the cloth while the filling is absent on the detecting picks of such take-up-controlling detector.

The take-up mechanism herein illustrated is substantially that shown and described in United States Patent to Roper, No. 807,580, 13

dated December 19, 1905, the take-up roll T being connected by a train of gear t t' t'' , with a worm t^3 , operatively connected with a rotatable shaft t^4 , on which is loosely mounted a driving member, shown as a sprocket t^5 , which in practice is continuously rotated from some moving part of the loom, as in the Roper patent referred to. A suitable clutch at t^6 normally connects the driving member t^5 and the shaft t^4 to rotate the latter and operate the take-up mechanism, a spring t^7 , Fig. 5, maintaining the clutch operative.

Herein I have provided a clutch-controlling arm 44, fulcrumed at 45 at the front of the loom and having a depending yoke-like portion 46 to coöperate with the clutch, the upper end of the clutch-controlling arm 44 being flattened at 47 to project over another member of the controlling means yet to be described.

Referring to Figs. 1, 6, and 7, the second filling detector or fork 48, having a tail 49, the fork-slide 50, movable in the fixed guide or stand 51, rigidly secured on the loom-frame, the weft-hammer W and its hook w to coöperate with the fork-tail when the fork is not tilted, and the notches $11^x 12^x 13^x$ at the outer end of the slide may be and are all substantially as in my Patent No. 789,291 referred to, except that herein the front end of the slide is provided with a forward extension 52, having an elongated longitudinal slot 53, (see Figs. 6, 7, and 8,) and the outer or left-hand edge of the extension is provided 35 with a diagonal or cam portion 54.

As in my Patent No. 789,291, a latch-carrier 27^x is herein shown provided with a latch 20^x to at times coöperate with the adjacent end of the knock-off lever N^x , fulcrumed at n^x , such coöperation rocking the knock-off lever and releasing the shipper S, Fig. 1, from its usual holding-notch in the plate N. The latch-carrier coöperates with the notches $11^x 12^x 13^x$, as in this patent, to 45 thereby effect stoppage of the loom if the slide 50 is moved outward a predetermined number of times in succession to thereby stop the loom in case of shuttle-mistreads—that is, if after filling replenishment the shuttle fails to thread the filling will be broken on the pick toward the replenishing side and another supply of filling will be inserted in the shuttle. If the mistread be due to clogging of the shuttle-eye or to an accidental bending 50 of the parts, the mechanism just described stops the loom after a predetermined number of replenishments in order to avoid emptying the hopper or filling-feeder unnecessarily. The upper end of the clutch-controlling arm 60 44 is located in front of the cam 54 on the fork-slide, so that when the latter is moved outward the action of said cam will serve to swing the controller 44 to the left, Fig. 5, to thereby render the clutch t^6 inoperative, ar- 65 resting take-up, and such outward move-

ment of the slide 50 is effected when on the pick toward the non-replenishing side or the loom the rork 48 detects filling failure.

In Fig. 7 the fork has not been tilted, and the weft-hammer hook w has engaged the fork-tail 49, and the slide has been moved forward by the forward stroke of the weft-hammer W. By inspection of said figure it will be seen that the take-up-controlling arm 44 has been moved into position to release take-up. I have herein provided means to prevent resumption of take-up until the fork 48 thereafter detects presence of filling and the device by which arrest of take-up is maintained, as shown in perspective in Fig. 9. 80 This device consists of an elongated body 55, having its front end enlarged and laterally extended at 56 to present an elongated vertical face 57, the part 56 resting upon the extension 52 of the slide and being retained in position thereon by a pin 58, which projects into the longitudinal slot 53. At its inner or rear end the body 55 is enlarged and downturned to present a lateral upright abutment 59 and a guide 60, the abutment and 90 guide straddling one side of the stand 51 and the adjacent side of the slide 50, as shown in Figs. 6 and 7, the clearance 61 between the abutment and the guide being wide enough to permit such positioning of the device. A lateral lug 62 on that side of the stand 51 extends in front of the guide 60 and limits forward movement of the device. (Shown separately in Fig. 9.) The abutment 59 lies in front of the weft-hammer path; but normally 100 the hammer will not coöperate therewith, as will be clear from an inspection of Fig. 6.

When the fork 48 detects filling failure and the slide 50 is thereupon moved forward, the position of the slide and the device just described is changed, the slide moving forward, as it were, underneath such device, so that the pin 58 will lie in the rear end of the slot 53, as in Fig. 7, and the straight edge 57 of the part 56 will form a continuation of the vertical face 50^x of the slide. The connection 63 between the guide 60 and the abutment 59 then drops into a notch 64 on the slide. Upon the outward movement of the latter the arm 44 is pushed to the left by the cam 54 and rests against the face 50^x , and were it not for the maintaining device (shown separately in Fig. 9) the arm 44 would return to normal position as the slide moves back. As the slide moves back it carries with it the maintaining device, and the face 57 then engages the arm 44 and maintains it in its inoperative position, so that the take-up clutch t^6 is held inoperative. If the fresh filling is properly laid on the return pick, its presence 125 is then detected by the fork 48, the latter being tilted, and as the weft-hammer W moves forward it engages the abutment 59 and moves the maintaining device forward with relation to the fork-slide into normal po- 130

sition, (shown in Fig. 6,) thereby releasing the arm 44, so that it returns to its normal position and take-up is resumed. If, on the other hand, the filling again fails on the return-pick, the relative position of the slide and maintaining device (shown in Fig. 7) will be retained as the slide moves outward and the arrest of take-up will be continued, so that after take-up has been arrested it is not resumed until the take-up-controlling fork 48 again detects the presence of filling. The front head 47 of the arm 44 projects over the lateral enlargement 56 of the maintaining device and serves to retain it in position on the slide, preventing it from jumping up or becoming misplaced.

The device for maintaining the arrest of take-up does not interfere at all with the proper operation of the mechanism for effecting loom-stoppage when mistreading takes place, as one operates entirely independently of the other.

When the slide 50 is moved forward, the pin 62 holds the maintaining device stationary, and it also serves as a stop to limit forward movement of the device when the abutment 59 thereof is engaged by the weft-hammer to reset it.

The take-up-controlling detector or fork detects on the picks of the shuttle toward the non-replenishing side of the loom, so that the two forks detect on alternate picks.

The lifting or tilting of the fork at the replenishing side by the positively-acting means described serves when filling is replenished to permit the fresh filling to be laid freely and in proper position under and back of the fork when the shuttle is picked from the box B* at the replenishing side, so that there is no possibility of the fork getting behind such filling. So, too, it will be manifest that as such positive raising of the right-hand fork takes place just after intact filling has tilted the fork initially the action upon the filling is very light and delicate—that is, as soon as the initial tilting has been effected the fork is withdrawn from the filling, so that any strain thereupon due to fork action is minimized and the delicacy of the detecting action is thereby increased.

My invention is not restricted to the particular form of take-up mechanism herein shown, although the latter is well adapted for use in connection with my invention; but it will be manifest that any other form of take-up mechanism can be employed so long as it is controlled by the adjacent filling-fork, and take-up action when arrested is maintained arrested, as herein provided for.

Various changes or modifications in the different details of my invention may be made by those skilled in the art without departing from the spirit and scope of my invention, as I have herein illustrated and described in detail but a single practical embodiment of such invention.

Having fully described my invention, what I claim as new, and desire to secure by Letters Patent, is—

1. In an organized loom, in combination, automatic filling-replenishing mechanism, a filling-detector to effect the actuation thereof, upon detection of filling absence, take-up mechanism, a second filling-detector to arrest the operation of the take-up mechanism upon detection of filling absence by said second detector, and means to maintain the take-up mechanism inoperative until presence of filling is again indicated by the second detector.

2. In an organized loom, in combination, mechanism to replenish automatically the running filling, a filling-detector adjacent said mechanism and solely controlling the same to effect filling replenishment on the pick upon which the detector detects filling failure, take-up mechanism, a second filling-detector, and controlling connections between it and the take-up mechanism, to arrest the operation thereof, upon detection of filling failure by the second detector, and to cause the take-up mechanism to resume its operation, when presence of filling is again detected by the same detector.

3. In a loom, two filling-forks, take-up mechanism, filling-replenishing mechanism, actuating means for the latter, controlled by one only of said forks, and means controlled by the other fork only to arrest take-up upon detection of filling failure by such fork, said means including a device to maintain the take-up mechanism inoperative until such fork again detects presence of filling.

4. In an organized loom provided with mechanism to replenish automatically the running filling, the following instrumentalities in combination, take-up mechanism including a clutch, two filling-detectors, one of which, upon detection of filling failure, effects the actuation of the replenishing mechanism, and controlling connections between the clutch and the other detector, to release the clutch and arrest take-up when said latter detector detects filling absence and to render the clutch operative thereby to effect resumption of take-up when such detector again detects presence of filling.

5. In an organized loom provided with mechanism to replenish automatically the running filling, the following instrumentalities in combination, take-up mechanism, including a clutch, two filling-detectors, one of which, upon detection of filling absence, effects the actuation of the replenishing mechanism on the pick on which such absence is detected, and clutch-actuating means governed by the other detector, to render the clutch inoperative upon detection of filling absence by such detector and thereafter render the clutch operative when presence of filling is again detected by the said detector.

6. A loom having, in combination, filling-replenishing mechanism at one side, a filling-fork at the same side, means to effect the actuation of said mechanism on the pick on which the said fork detects filling failure, a second filling-fork at the other side of the loom, said forks detecting on alternate picks, and take-up mechanism stopped by or through detection of filling failure by the second fork and thereafter started by detection of filling presence by said second fork.

7. In a loom provided with a shuttle adapted to contain a supply of filling, and mechanism to provide the shuttle with a fresh supply of filling, in combination, two filling-forks, at opposite sides of the loom and detecting on alternate picks, actuation of said mechanism being effected on the detecting pick by or through detection, by the adjacent fork, of filling failure as the shuttle moves toward the replenishing mechanism, means to withdraw such fork from the shuttle-path and also prevent filling-failure indication thereby on the intervening picks, and take-up mechanism the operation of which is controlled wholly by the other of the two filling-forks.

8. In a loom, two filling-forks, take-up mechanism, filling-replenishing mechanism, actuating means for the latter controlled by one of said forks, means to positively tilt the latter upon the operation of the replenishing mechanism, to clear the outgoing replenished shuttle and prevent indication of filling failure on that pick, and means controlled by the other fork to arrest take-up upon detection of filling failure by such fork and to cause resumption of take-up when presence of filling is again detected by the last-named fork.

9. In a loom, in combination, mechanism to replenish filling in the running shuttle, two filling-detectors located at opposite sides of the loom, controlling connections between one only of said detectors and said mechanism to effect actuation of the latter upon detection of filling absence by the former, take-up mechanism, and connections between the same and the other detector only, to arrest the operation of said mechanism upon detection of filling absence by its controlling-detector and to maintain such arrest until filling presence is again detected by such detector.

10. In a loom, in combination, two filling-detectors, mechanism the actuation of which is effected by or through one of said detectors, to automatically replenish the running filling on the pick on which non-continuity of filling is detected by such detector, take-up mechanism, and means to arrest the operation thereof from detection of filling failure by the other of said detectors until the latter again detects the presence of filling.

11. In a loom, a shuttle adapted to contain a supply of filling, a detector to indicate non-

continuity or the lifting on alternate picks, mechanism actuated by or through such indication of the detector to provide automatically, the shuttle with fresh filling on the indicating pick, a second detector to indicate non-continuity of filling on the intervening picks, and take-up mechanism the operation of which is arrested upon such indication of the second detector and resumed when such detector again detects continuity of filling.

12. In a loom provided with filling-replenishing mechanism, a shuttle adapted to contain a supply of filling, and take-up mechanism, in combination, a filling-fork to indicate filling failure on each pick toward the replenishing mechanism, means whereby such indication effects automatically the actuation of such mechanism on the same pick, a second filling-fork to indicate filling failure on each pick away from the replenishing mechanism, and controlling connections between the second fork and the take-up mechanism, to arrest the operation of the latter when and while filling failure is indicated by the second fork.

13. In a loom provided with filling-replenishing mechanism, a shuttle adapted to contain a supply of filling, and take-up mechanism, in combination, a filling-fork to indicate filling failure on each pick toward the replenishing mechanism, means whereby such indication effects automatically the actuation of such mechanism on the same pick, a second filling-fork to indicate filling failure on each pick away from the replenishing mechanism, controlling connections between the second fork and the take-up mechanism, to arrest the operation of the latter when and while filling failure is indicated by the second fork, a shipper, and means to release the same when said second fork has indicated filling failure a predetermined number of times successively.

14. In a loom, an instrumentality to lay the filling, means to intermittently engage intact filling and to detect non-continuity of the latter, a fixed support for said means, mechanism the actuation of which is effected by or through said means, to automatically provide said instrumentality with fresh filling on the pick on which non-continuity is detected, and means to coöperate directly with and withhold the detecting means from the path of the filling-laying instrumentality on the return pick thereof.

15. In a loom, an instrumentality to lay the filling, means to intermittently engage intact filling and to detect non-continuity of the latter, a stationary support for said means, mechanism the actuation of which is effected by or through said means, to automatically provide said instrumentality with fresh filling on the pick on which non-continuity is detected, means to prevent engage-

ment of the detecting means and the filling-laying instrumentality on the return pick thereof, and other means operative on such return pick to prevent actuation of the filling-supplying mechanism.

16. In a loom, a shuttle to contain a supply of filling, a tilting fork to detect non-continuity of filling on alternate picks, a stationary support on which said fork is fulcrumed, mechanism actuated by or through non-tilting of the fork to automatically provide the shuttle with a fresh supply of filling on the same pick as that on which non-continuity of filling is detected, and means to tilt the fork out of the path of the shuttle on the return or non-detecting pick.

17. In a loom, in combination, a shuttle to contain a supply of filling, a fork adapted to be tilted by the filling when the latter is intact, a fixed support on which the fork is fulcrumed, filling-replenishing mechanism operated by or through non-tilting of the fork, on the pick on which non-continuity of the filling is detected, to provide the shuttle with fresh filling, means to tilt the fork out of the shuttle-path on the return pick, and a device to prevent return of the fork to detecting position until after such return pick has been completed.

18. In a loom, a shuttle to contain a supply of filling, mechanism located at one side of the loom to automatically provide the shuttle with a fresh supply of filling, a filling-fork at the same side of the loom, to indicate filling failure, means whereby indicatory action of said detector on the pick of the shuttle toward said mechanism effects actuation of the latter to change the shuttle-filling on the indicated pick, means to positively tilt the fork out of the shuttle-path on the return pick and maintain it tilted until the next pick of the shuttle toward the replenishing side of the loom, and a vibrating actuator for said means.

19. In a loom, a shuttle to contain a supply of filling, mechanism located at one side of the loom to automatically provide the shuttle with a fresh supply of filling, a filling-fork at the same side of the loom, to indicate filling failure, means whereby indicatory action of said detector on the pick of the shuttle toward said mechanism effects actuation of the latter to change the shuttle-filling on the indicated pick, means to positively tilt the fork out of the shuttle-path on the return pick and maintain it tilted until the next pick of the shuttle toward the replenishing side of the loom, and a device to deaden or reduce vibration of the fork when the latter is freed from the control of said tilting means.

20. In a loom, a shuttle to contain a supply of filling, a filling-fork to indicate filling failure, mechanism controlled and actuated by or through indicating action of said detector to automatically provide the shuttle

with a fresh supply of filling on the pick on which such indicating action occurs, a second filling-fork, take-up mechanism the operation whereof is arrested by or through filling-failure indication of such fork, said forks detecting on alternate picks, and means to prevent indication of filling absence by the first-named fork on the detecting pick of the other fork.

21. In a loom, a lay, a shuttle to contain a supply of filling, replenishing mechanism, a normally inoperative actuator therefor, movable with the lay, a tilting detector to indicate failure of filling when laid toward the replenishing mechanism, said actuator being controlled and rendered operative by or through indicating action of the detector, to effect the actuation of the replenishing mechanism, by the forward beat of the lay, on the detecting pick, and means to positively tilt the detector and maintain it tilted on the return pick, to enable the said detector to clear the shuttle and also to prevent actuation of the replenishing mechanism on such return pick.

22. In a loom, a lay, a shuttle to contain a supply of filling, replenishing mechanism, a normally inoperative actuator therefor, movable with the lay, a tilting detector to indicate failure of filling when laid toward the replenishing mechanism, a controller for said actuator, locked in active position by or through the detector when filling absence is indicated thereby, to cause the actuator to effect the actuation of the replenishing mechanism as the lay beats up on the detecting pick, tilting of the detector releasing the controller and permitting it to remain inactive with respect to the actuator, and means to positively tilt the detector on the return pick of the shuttle, to clear the latter and also to prevent filling-replenishing action on such return pick.

23. In a loom, a lay, a shuttle to contain a supply of filling, replenishing mechanism, a normally inoperative actuator therefor, movable with the lay, a tilting detector to indicate failure of filling when laid toward the replenishing mechanism, a controller for said actuator, locked in active position by or through the detector when filling absence is indicated thereby, to cause the actuator to effect the actuation of the replenishing mechanism as the lay beats up on the detecting pick, tilting of the detector releasing the controller and permitting it to remain inactive with respect to the actuator, and a vibrating member acting on the non-detecting picks to tilt the detector out of the shuttle-path and move into inoperative position said controller, the said member permitting the detector to return to detecting position, and the controller into position to be locked, prior to forward movement of the lay to the detecting-point on each detecting pick.

24. In a loom, a lay, a shuttle to contain a supply of filling, replenishing mechanism, a normally inoperative actuator therefor, movable with the lay, a tilting fork to detect failure of filling when laid toward the replenishing mechanism, a fixed support on which the fork is fulcrumed, a controller for said actuator, fulcrumed on the support and locked in active position by the fork when the latter is not tilted, to cause the actuator to effect the actuation of the replenishing mechanism on the detecting pick, tilting of the fork releasing the controller and permitting it to rock freely with respect to the actuator, and means independent of the filling to tilt the fork out of the shuttle-path on the return pick of the shuttle, to also release the controller and prevent filling-replenishing action on such return pick, said means acting upon the controller thereafter to retard its return to active position until it is time for the fork to return to detecting position.
25. In a loom, a lay, a shuttle to contain a supply of filling, replenishing mechanism, a normally inoperative actuator therefor, movable with the lay, a tilting fork to detect failure of filling when laid toward the replenishing mechanism, a locking extension on the fork, a fixed support for the latter, a controller fulcrumed on the support, provided with a foot to set the actuator and with a shoulder to be engaged by the locking extension when the fork is not tilted, whereby the actuator effects the actuation of the replenishing mechanism as the lay beats up on the detecting pick, tilting of the fork unlocking the controller and permitting it to rock freely with respect to the actuator, and means to positively tilt the fork on the return pick, to thereby clear the shuttle, said means also preventing co-operation of the locking extension and the shoulder of the controller until after the shuttle has started on the next detecting pick.
26. In a loom, a lay, a shuttle to contain a supply of filling, filling-replenishing mechanism, a normally inoperative actuating-bunter therefor movable with and also relatively to the lay, a filling-fork adapted to be tilted by intact filling when laid toward the replenishing mechanism, means to operatively position the bunter by or through indication of filling failure by the fork, to actuate the replenishing mechanism on the forward beat of the lay immediately succeeding such indication, and means independent of the filling to tilt the fork on the intervening or return picks, engagement of the shuttle by the fork on a detecting pick tilting the fork and thereby causing the latter to act as a shuttle-feeler and prevent filling replenishment.
27. In a loom, a shuttle to contain a supply of filling, filling-replenishing mechanism at one side of the loom, a filling-fork adapted to be tilted by intact filling when laid toward the replenishing mechanism, a support on which the fork is fulcrumed, a depending, swinging guard on the support to prevent the filling from passing under the fork, means operative by or through detection of filling failure by said fork to effect the actuation of the replenishing mechanism on the pick on which such failure is detected, and means to tilt the fork independently of the filling on the return, or non-detecting picks, to prevent actuation of the replenishing mechanism.
28. In a loom, a lay, a shuttle to contain a supply of filling, filling-replenishing mechanism at one side of the loom, an actuating-bunter therefor carried by the lay and movable relatively thereto, a tilting filling-fork to indicate the condition of filling on each pick of the shuttle toward the replenishing mechanism, means to operatively position the bunter on the forward beat of the lay upon such picks, if the fork is not tilted, to effect filling replenishment on the same pick, and a vibrating member to tilt the fork before the shuttle begins its return pick and to thereafter positively insure return of the fork to detecting position before the lay reaches the detecting-point on the next forward beat.
29. In a loom, a shuttle to contain a supply of filling, filling-replenishing mechanism at one side of the loom, a filling-fork at the same side, adapted to be tilted by intact filling on each pick of the shuttle toward the replenishing mechanism, means to positively tilt the fork on each intervening pick, and means rendered operative by or through detection of filling failure by said fork to cause the actuation of the replenishing mechanism on the pick on which failure is detected, engagement of the fork with the shuttle when improperly boxed on a detecting pick tilting the fork and thereby preventing actuation of the replenishing mechanism.
30. In an organized loom provided with filling-replenishing mechanism, in combination, two filling-forks to detect filling failure on alternate picks, take-up mechanism the operation of which is arrested by or through detection of filling failure by one of the forks, means to positively tilt the other fork on the detecting pick of the said take-up-controlling fork, and means to cause the actuation of the replenishing mechanism by or through detection of filling failure by the fork which is positively tilted on its non-detecting pick.
31. In a loom provided with filling-replenishing mechanism a filling-fork adapted to act as a shuttle-feeler to prevent replenishment of filling when the shuttle is improperly boxed.
32. In a loom provided with filling-replenishing mechanism, at one side thereof, a filling-fork to control the operation of said mechanism and located at the same side of the loom, and a stationary support on which the fork is mounted.

33. In a loom provided with filling-replenishing mechanism, at one side thereof, a filling-fork to control the operation of said mechanism, and means to tilt and maintain said fork inoperative during the pick of the shuttle from the replenishing side of the loom.
34. In a loom provided with filling-replenishing mechanism, at one side thereof, a filling-fork adjacent said mechanism, to effect actuation of the latter on the pick on which the fork detects filling failure, and means to

tilt the fork positively immediately following replenishment, whereby the fresh filling is permitted to be laid under and back of the tilted fork.

In testimony whereof I have signed my name to this specification in the presence of two subscribing witnesses.

JONAS NORTHRUP.
